UNITED STATES PATENT OFFICE.

RALPH W. E. SMITH, OF PORTLAND, MAINE.

LOCK FOR MAIL BAGS.

Application filed October 29, 1921. Serial No. 511,424.

To all whom it may concern:

Be it known that I, RALPH W. E. SMITH, a citizen of the United States, residing at Portland, in the county of Cumberland and State of Maine, have invented certain new and useful Improvements in Locks for Mail Bags, of which the following is a specification.

My invention relates to a lock for mail bags to take the place of the strap and staple with the padlock ordinarily used for this purpose.

The object of my invention is to construct the locking device to be applied to the neck 15 of the mail bag whatever the size of diameter of the neck so that it can be quickly locked and released in any desired position.

The device as I prefer to construct it, consists of an arcuate casing fitting around 20 the neck of the bag with a strap having on its end a bolt provided with ratchet teeth adapted to slide into the casing and to be caught therein by a pawl with a suitable key entering the casing for releasing the pawl 25 and a suitable slot within the casing for sliding in a tag indicating the post-office.

With such a device, it is only necessary to close it around the neck of the bag, push the bolt into its recess where it will be 30 automatically locked by the retaining pawl and quickly releasable when desired by the use of the key.

On the outside surface of the casing is a recess through which the name of the post-office is visible.

The device does the work of the padlock, strap and staple now in use and is a very simple and effective device for the purpose.

I have illustrated my invention by means 40 of the accompanying drawing in which similar reference letters indicate similar parts.

Fig. 1 is a plan of the locking device.

Fig. 2 is an elevation of the upper end of the bag with the lock in place,

Fig. 3 is a perspective of the tag retaining slide,

Fig. 4 is a perspective of the multiple spring acting to close the pawl,

Fig. 5 is a horizontal section through the 50 bag and lock.

Fig. 6 is a side elevation of the key,

Fig. 7 is a section through the tumblers of the lock taken on the line 1—1 of Fig. 5,

Fig. 8 is a perspective section of the end 55 of the casing showing the tag in place,

Fig. 9 is an elevation of the casing,

Fig. 10 is a plan of the device formed straight as distinguished from the arcuate form, the latter being adapted especially for mail bags and,

Fig. 11 is an elevation of the end of the casing showing the tag receiving recess.

Referring to the drawing:

1 represents the bag and 2 is a flexible strap secured by one end to the bag, the other end being free to pass around the neck of the same. On the free end of the strap 2 is an arcuate bolt 3 containing ratchet teeth 6 for locking the bolt in place and having a projection handle 2' by which it is pushed in and drawn out.

The bolt is received in a hollow casing 4 secured to the bag and the fixed end of the strap by rivets 5 or other suitable means.

Both the bolt 3 and the casing 4 are formed in the arc of a circle so that the bolt may be pushed into the casing from the open end thereof as far as may be necessary to completely close the mouth of the bag.

Ratchet teeth 6 are formed on the outer edge of the bolt 3 and extend sufficiently far back from the end so as to cover different sizes of bag and to make sure the strap is closed completely.

The bolt 3 is held in locked position by a spring actuated pawl which is made up of a plurality of thin pawls 8 placed side by side on the shaft 7.

These thin pawls acting together or separately engage the teeth 6 to hold the bolt locked.

A multiple spring 9 having a plurality of spring members is secured to the casing and each spring is positioned to press downward upon one of the corresponding pawls 8 so that each separate pawl is spring actuated and is in position to engage one of the teeth of the bolt.

The pawl is released by a key 10 having wards 10' which press down on each of the sections of the pawl. The wards are of length so that when the key is turned, they lift each pawl out of engagement with its tooth.

The length of the wards and the thickness of the corresponding section must exactly correspond so that the effect of the entire combination will be to disengage the pawl when the key is turned.

Means are provided for inserting in the outer portion of the casing a tag 15 marked

to designate the post-office which may be the destination of the bag.

For this purpose, a longitudinal slot is formed in the casing immediately outside 5 the slot containing the bolt. This slot 11 is opened at one end so that the elongated tag 15 may be slipped into place and the outer face of the casing is cut away to form an opening 12 through which the face of the 10 tag may be seen.

Means are provided for holding the tag in place longitudinally so that it cannot slip out of the end where it is inserted. For this purpose, I provide a slide 14 which slips on 15 the bolt 3 with slight friction so that it will normally remain in place wherever it is left.

At one end of the slide 14 is a projection 13 which extends so as to close the end of the 20 slot 11.

In operation, the strap and bolt being free from the casing, the bag is filled, the strap passed around its neck, the bolt is inserted into the casing and pushed inward until it 25 is locked by the action of the pawls engaging the ratchet teeth.

It is evident that the distance the bolt passes into the casing will be governed by

the size of the neck of the bag but at whatever position the bolt finally takes, the slide 30 14 is pushed upward to the end of the casing thereby holding the tag securely in place.

It will be seen that the entire locking device is securely attached to the bag and that the whole arrangement is very compact and 35 simple.

In Fig. 10, I have shown the device made in a straight line in place of the curve illustrated in Fig. 1 so that a bag of rectangular cross section may be closed as well as a bag 40 having a circular cross section.

I claim:

A lock for mail bags consisting of a strap or the like, an arcuate casing secured to one end of the strap, an arcuate bolt secured to the other end of the strap having ratchet teeth and adapted to slide into said casing, a pawl for engaging said ratchet teeth, a key for releasing the same, said casing having 45 a longitudinal slot open at one end and at its face into which a tag may be slipped and a frictionally held slide embracing and a 50 adapted to move on said strap for retaining said tag within the casing.

RALPH W. E. SMITH.
